CLAIM

The ornamental design for a remote control, as shown and described.

DESCRIPTION

FIG. 1 is a front, bottom, and right side perspective view of a remote control showing our new design;

FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the figures represent portions of the remote control that form no part of the claimed design.

1 Claim, 4 Drawing Sheets(56)
